UNITED STATES PATENT OFFICE

168,627

SLIDE PROJECTOR

Gerhard Lessman, Chicago, Ill., assignor to De
Vry Corporation, Chicago, Ill., a corporation of
Illinois

Application July 1, 1952, Serial No. 20,429

Term of patent 14 years

(Cl. D61—1)

To all whom it may concern:

Be it known that I, Gerhard Lessman, a citizen of the United States and a resident of Chicago, in the county of Cook and State of Illinois, have invented a new, original, and ornamental Design for a Slide Projector, of which the following is a specification, reference being had to the accompanying drawing forming a part thereof, and in which

Fig. 1 is a perspective view of a slide projector showing my new design;

Fig. 2 is a perspective view thereof from the opposite side; and

Fig. 3 is a rear elevational view thereof.

I claim:

The ornamental design for a slide projector, as shown.

GERHARD LESSMAN.
